UNITED STATES PATENT OFFICE

ALF JOHNSON, OF REVLOC, PENNSYLVANIA

HIGHWAY-GUARD-FENCE CONSTRUCTION

Application filed May 29, 1930. Serial No. 457,218.

This invention relates to a highway guard fence and has for its primary object to provide, in a manner as hereinafter set forth, a fence of this character embodying a novel construction and arrangement of parts for supporting one or more cables on a series of supporting posts in laterally spaced relation thereto in a manner to effectively prevent vehicles which contact with the said cables from colliding with the supporting posts with the resultant damage to the vehicle and posts and possible injury to the occupants of said vehicle.

Other objects of the invention are to provide a highway guard fence of the character described which will be comparatively simple in construction, strong, durable, efficient in its use and which may be manufactured at low cost.

All of the foregoing and still further objects and advantages of the invention may become apparent from a study of the following specification, taken in connection with the accompanying drawings wherein like characters of reference designate corresponding parts throughout the several views, and wherein:—

Figure 1 is a top plan view showing a highway guard fence constructed in accordance with this invention with some of the cable supporting brackets omitted from the supporting posts.

Figure 2 is a fragmentary detail view in side elevation on an enlarged scale showing one of the cable supporting brackets or arms.

Figure 3 is a fragmentary detail view on an enlarged scale in horizontal section taken substantially on the line 3—3 of Figure 2 looking in the direction indicated by the arrows.

Referring to the drawings in detail, it will be seen that the reference numeral 1 designates a vertical supporting post which is inserted in the ground in any suitable manner, a series of said posts being provided and mounted in spaced relation as is usual.

Disposed vertically against the side of each of the posts 1 which is toward the highway is a substantially U-shaped bracket 2 having an opening in its intermediate portion

through which extends an eye bolt 3 which passes transversely through the post and has mounted on its threaded end a washer 4 and a securing nut 5. The reference numeral 6 designates the horizontally disposed eye of said eye bolt 3. The bracket 2 includes the outwardly extending horizontally disposed arms 7 the free ends of which are provided with arcuate recesses in vertical alignment with the opening in the eye 6.

A horizontally disposed flat metallic arm 8 has formed integrally on one end, the vertically spaced eyes 9 which are in vertical alignment with the opening in the eye 6, said eyes 9 being seated in the arcuate recesses in the opposite ends of the bracket 2. A headed pin 10 passes through the eyes 9 and 6 and a cotter key 11 is disposed transversely through the lower end portion of said pin to secure the same in position. The free end portion of the arm 8 has formed therein the longitudinally spaced openings 12 for the passage of the guard cables 13.

The eye bolts 3 constitute means for rigidly clamping the arm 8 in horizontal position against the bracket 2 when the nut 5 is threaded against or toward the post 1. The eyes 9 seat snugly in the recesses in the opposite end of the bracket 2 and in this manner the arms 8 are frictionally held against swinging movement in a horizontal plane on the eye bolts 3 unless subjected to considerable lateral strain, as when engaged by a moving vehicle.

It will thus be seen that I have provided a highway guard fence of a construction whereby a vehicle or other body coming into contact with the guard cables will be held away from the supporting post until said vehicle has been brought to a stop or the speed thereof materially decreased. It will further be apparent that any desired number of cables 13 may be installed by increasing the number of openings 12 in the arms 8. If desired, two or more of the cable supporting structures may be mounted in vertical alignment of each of the posts 1 and the bolts 10 made long enough to pass through all of same.

It is believed that the many advantages

of a highway guard fence constructed in accordance with this invention will be readily understood and although the preferred embodiment of the invention is as illustrated and described, it is to be understood that changes in the details of construction may be had which will fall within the scope of the invention as claimed.

What is claimed is:—

- 10 1. A highway guard fence of the character described comprising a vertical supporting post, a bracket disposed against one side of the post having superposed, horizontally extending opposite end portions provided with arcuate recesses in their free ends, an eye bolt extending through an intermediate portion of the bracket and adjustably anchored in the post, a cable supporting arm, aligned spaced eyes on one end of the cable supporting arm in alignment with the eye of the eye bolt, and seated in the recesses in the bracket, said eye bolt constituting means for supporting the bracket on the post, a coupling pin extending through the eye bolt and through the eyes of the arms.
- 15 2. A highway guard fence of the character described comprising a vertical supporting post, an eye bolt extending transversely through the supporting post, a vertically disposed bracket mounted on the eye bolt in engagement with one side of the supporting post and including horizontally disposed outwardly projecting opposite end portions having arcuate recesses therein, said recesses disposed in vertical alignment with the eye of the eye bolt, an arm, integral, spaced, aligned eyes on one end of the arm disposed above and below the eye of the eye bolt and seated in the recesses in the bracket, a coupling pin extending through the eyes of the arm and the eye of the eye bolt, a nut threaded on the eye bolt for engagement with the post in a manner to clamp the arm and the bracket thereagainst, said arm frictionally engaged with the bracket and having cable receiving openings in its free end portion and constituting means for supporting the cables in spaced relation with respect to the posts.

50 In testimony whereof I affix my signature.
ALF JOHNSON.
